UNITED STATES PATENT OFFICE.

WILLIAM SPARKS, OF JACKSON, MICHIGAN, ASSIGNOR TO THE SPARKS-WITHINGTON COMPANY, OF JACKSON, MICHIGAN, A CORPORATION OF OHIO.

SIGNALING DEVICE.

Application filed March 20, 1924. Serial No. 700,504.

This invention relates to certain new and useful improvements in signaling devices.

The main object of the invention relates to the provision of hardened bearing for the forward end of the armature shaft of the motor combined with the novel means and structure for effecting easy and efficient lubrication of the same.

Preferably, the construction is such that lubricant may be supplied to this bearing from the exterior of the signaling device and without removing the motor cover.

Other objects and advantages relate to the details of the structure and form of the parts, all as will more fully appear from the following description taken in connection with the accompanying drawings in which:—

Figure 1 is a longitudinal sectional view through the signaling device.

Figure 2 is a section on line 2—2, Figure 1. Figure 3 is a section on line 3—3, Figure 2.

The general structure of horn or signaling device here illustrated is substantially the same as that disclosed in my copending application, Serial Number 493,498, filed August 18, 1921, and this invention is more particularly an improvement upon the structure described and claimed in my copending application, Serial Number 676,749, filed November 30, 24, 1923.

The signal shown comprises the usual resonator —1—, front diaphragm case section —2— and rear diaphragm case section —4—.

The case section —4— carries a U-shaped motor case —5— which may be secured to the case section in any suitable manner. The rear bearing for the armature shaft —6— of the electric motor is formed in the U-shaped motor case —5— and any desired means of adjustment may be provided, as the same forms no portion of the invention here claimed.

The motor shaft —6— extends forwardly through the case section —4— and has its bearing —7— formed in a hardened sheet —12— of metal such as steel as illustrated, of substantially rectangular form and lying in substantially flat contact with the base of the case section —4— and secured to the case section —4— in any suitable manner as by rivets —8—.

The base —9— of the case section —4— is provided with two radial grooves —14— and —21— formed in any suitable manner as by depressing portions of the case section, and

preferably these radial grooves lie substantially in the same diameter of the base of the case section and merge at their inner ends into a further depressed, and in this illustration, substantially rectangular portion —11— of the base —9—.

Between the hardened steel sheet —12— and the depressed portion —11— of the casing, there is positioned an absorbent disk —16— of felt or similar material for retaining lubricant about the bearing. This disk has a substantially centrally disposed opening through which the armature shaft extends.

The steel sheet —12—, in like manner as the base —9— of the casing, is formed with two grooves —14— and —15— extending radially of the base —9—, and the groove —14— registers with the groove —10— in the base —9— so as to form a conduit extending radially of the base —9— and leading to the depressed portion —10—.

In like manner, the groove —15— registers with the groove —21— to form an oil conduit leading to the depressed portion —10— and as these oil conduits are substantially diametrically disposed, it will be apparent that the horn may be mounted either side up and one of the passages will constitute a conduit for conveying oil to the bearing by gravity.

The case section —4—, in the usual manner, is formed with a cylindrical ledge —17— upon which the motor casing —18— is telescoped and this ledge is formed with perforations —19— leading to the respective oil conduits, and the motor casing is likewise formed with perforations —20— registering with the respective perforations —19— so that the conduits leading to the depression —10— open through the ledge and through the motor casing to the exterior of the signaling device, thereby permitting lubricant to be supplied to the bearing from the exterior of the signaling device without removing the motor casing —18—.

The armature shaft, in the usual manner, is provided at its forward end with a cam or toothed wheel —22— adapted to contact with a wear piece on the diaphragm —24—, the edge of the diaphragm being confined between the case sections —2— and —4— in the usual manner.

Although I have shown and described a specific construction of device, as illustrative of a perhaps preferred embodiment of my invention, I do not desire to restrict myself to

the details of form or structure of the device as various changes may be made within the scope of the appended claims.

I claim:

- 5 1. A horn comprising an armature shaft, a rear diaphragm case section having a base formed with an opening for the passage of said shaft, a plate secured to the base of the case section and extending to the edge of the 10 base and having a hardened bearing for the armature shaft in alignment with the opening through the base, a radial groove in the case section extending from the bearing and leading to the edge of the base, and an opening 15 through the case section at the termination of said groove.
2. A horn comprising an armature shaft, a rear diaphragm case section having a base provided with a depressed portion formed 20 with an opening for the passage of said shaft, a plate secured to the base of the case section and having a hardened bearing for the armature shaft in alignment with the opening through the base, a radial groove in the case 25 section leading to the edge of the base, and a radial groove in the said plate supplementing the grooves in the base to form a lubricant conduit leading to the edge of the base and an opening through the case section at 30 the termination of said groove.
3. A horn comprising an armature shaft, a rear diaphragm case section having a base provided with a depressed portion formed 35 with an opening for the passage of said shaft, a plate rigidly secured to the base of the case section and having an opening through which the shaft extends and forming with said depressed portion a lubricant chamber surrounding the shaft and said base and plate 40 having portions spaced apart to form a conduit leading from said lubricant chamber to the edge of the base for conveying lubricant

to said chamber and an opening through the case section at the termination of said conduit.

4. A horn comprising an armature shaft, a rear diaphragm case section having a base provided with a depressed portion formed with an opening for the passage of said shaft, a plate rigidly secured to the base of the case section and having an opening through which the shaft extends and forming with said depressed portion a lubricant chamber surrounding the shaft and said base and plate having portions spaced apart to form a conduit leading from said lubricant chamber to the edge of the base for conveying lubricant to said chamber, said case section having an opening aligned with said conduit permitting the passage of lubricant to the conduit, and a motor casing enclosing the shaft and having an opening aligned with the opening in the case section.

5. A horn comprising an armature shaft, a rear diaphragm case section having a base provided with a depressed portion formed with an opening for the passage of said shaft, a plate rigidly secured to the case section and including a hardened cylinder alined with the opening in the depressed portion and which constitutes the forward bearing for said shaft, and said plate being spaced from said depressed portion to form a lubricant chamber surrounding the shaft, and said base and plate having portions spaced apart to form a conduit leading from said lubricant chamber to the edge of the base for conveying lubricant to said chamber, and said case section having an opening alined with said conduit to permit the passage of lubricant to the conduit.

In witness whereof I have hereunto set my hand this 23rd day of February, 1924.

WILLIAM SPARKS.
